JET CARBURETOR

Earl G. Eckenberg, Los Angeles, Calif.

Application January 8, 1944, Serial No. 517,589

1 Claim. (Cl. 261—41)

This specification constitutes an improvement upon and a continuation in part of my previous application Serial Number 472,531, filed January 15, 1943, entitled "Jet carburetors."

The objects of the invention are as follows:

1. To provide a simple, practical and efficient carburetor of the injection type for internal combustion engines.
2. To provide a carburetor in which there is no wet well and no float, thereby enabling the device to function with equal facility when in inverted or any other position.
3. To provide a carburetor having a pre-combustion mixing chamber for fuel and air, whereby all portions of the combustible mixture are thoroughly blended.
4. To provide a novel, yet simple and practical mechanical arrangement to control jet admission of fuel to a plural number of orifices in the throat of a Venturi tube of the carburetor for mixing with incoming air.

Other objects, features and advantages of the invention may be observed in the appended specification and drawing.

In the drawing:

Figure 1 is an enlarged detail showing a portion of the carburetor, the figure is particularly designed to show in detail the means used to control admission of fuel to the throat of the Venturi tube of the carburetor.

Figure 2 is a further detail showing the fuel regulating valve detached from the carburetor.

Figure 3 is a transverse sectional view taken on line 88, Figure 2, and is designed to show further detail of construction adapted to pass fuel through the fuel control valve.

The carburetor of this invention includes an upper cylindrical portion 12 and a lower bowl-like portion 14 in which fuel and air are thoroughly admixed before moving into the manifold of an engine, and it also includes means to throttle the volume of fuel admitted to an engine.

The mixing bowl 14 is formed with a smooth inner surface 16 to facilitate movement of vaporized fuel through the device to the intake manifold. The lower face 18 of the bowl is adapted to be fixedly secured upon an intake manifold in any practical manner, while the upper surface 20 of the bowl is adapted to receive the cylinder 12 above referred to.

The lower end of the cylinder is formed with a flange 28 which is bored at 30 in a direction across the longitudinal axis of the cylinder to receive a valve 32 which is movable longitudinally within the bore 30 to control admission of liquid

fuel. A tubular extension 40 is secured at its one end to the flange 28, while the other of the ends thereof is provided with threads for connection with an incoming fuel line not shown in the drawing.

The tubular extension 40 is formed in such manner as to provide a housing for a pinion-wheel 42 which in turn is in mesh with a circular rack 44 having a bored center. The rack is of course movable within the extension as will be more particularly set forth in the description of operation.

As shown in Figures 1 and 3 the valve 32 is tubular in exterior configuration and is formed with a head 33 which is slotted at 33m across the face thereof, while the body of the valve is of reduced section at point 32b adjacent the head 33m and extending forwardly a limited distance therefrom. A bushing 37 having a slotted head-portion 37a is threaded secured in the tubular extension 40 and is adapted to hold the valve 32 in the end alignment therewith. The bushing is also formed with an opening 32g of somewhat greater diameter than the reduced section 32b, whereby an annular space 32h is formed between the bushing 37 and the reduced section 32b of the valve 32 thus enabling fluid to pass therethrough. As shown in Figures 1 and 3 the one end of the bored center 40e is slightly recessed at 40n to form an abutment for the head 33, while the bushing 37 pressing against the other side of the head 33 provides an adequate support for the valve in its functional position.

The body of the valve 32 is bored and threaded at 32c to receive a needle valve 39 which is manually adjustable to minutely regulate the effective area of an orifice 41 and the volume of liquid fuel which may pass therethrough from the jet 43 positioned in the valve body 32 and extending from the exterior thereof to a point adjacent the inner end of the needle valve 39.

The jet or passage-way 41 terminates in a flared opening 45 which is thus shaped to accommodate an increased volume of fuel from the jets or passage-ways 43a, 43b, and 43c which extend from the interior of the valve body to the exterior thereof and which are so located along the length thereof as to be normally concealed and covered by the sides of the bore 30 when the valve is in what may be termed engine idling position.

The bore 30 and the open end of the valve 32 terminate in a passage-way 30a in open communication with a circular manifold formed as a groove 30b in the lower and outer face of the

Venturi tube 26, thus providing in effect a distribution manifold from which a plural number of jets 52 extend convergently toward and which terminate in the throat 26b of the Venturi tube 26.

In order to better control the intake of vaporized fuel I place a valve 60 in the throat of the Venturi tube 26 in such manner that the face thereof is seated against the under and divergent side of the Venturi throat 26b.

Reference has previously been made to the pinion-wheel 42, this element is rotated or rocked by means of a shaft 70 which extends through a bearing 72 formed as an extension of the part 40. A suitable packing gland may be used to seal the shaft 70 with respect to the bearing 72, while the free end of the shaft 70 is provided with an arm 15 manual control to control movement of the rack.

A description of the operation of the carburetor of this invention is substantially as follows:

Assuming that the carburetor has been installed upon the intake manifold of an engine and that a control therefor has been functionally connected with an accelerator of an automobile or with a hand throttle as the case may be, and that the threaded end of the extension 40 is connected with a fuel supply line, then in that case, as in the manner of any internal combustion engine, it is only necessary that the ignition key or switch be closed and the engine given an initial impulse to start the same.

After the engine has been started, a fuel pump, not shown, forces raw liquid fuel into the extension 40 and through the interior of the rack 44, thence through the slots 33m in the head 33 of the valve body 32, thence by reason of the reduced section of the body of the valve 32, the fuel flows through the bushing 37 and the slotted head 31a and enters the cavity B from which a portion of the fuel will flow through the jet 43 and past the needle valve 39, thence through the jet 41 and the flared opening 45 of the valve 32, from which point the fuel will enter the manifold ring 30b and the several lateral jets 52 extending therefrom, thereby entering the throat of the Venturi tube at its point of greatest constriction.

The preceding statement covers idling position only for as above set forth fuel has only passed through jet 43, however, upon movement of the carburetor control gear 42 and the rack 44, the

body of the valve 32 is likewise moved in the direction indicated by the arrow C thereby uncovering one or more of the jets 43a, 43b, and 43c.

Uncovering of the last mentioned jets admits 5 additional fuel to the complete capacity of the carburetor. Concurrently with manipulation of the valve 32, movement of the carburetor control causes the valve 60 to be moved with respect to the seat 60a, thereby controlling the volume of 10 combustible fuel admitted to the engine.

The preceding matter is believed to be completely descriptive of my new and improved injection carburetor, the essence of the invention of which resides in extreme simplicity of construction, unfailing operation, increased efficiency over conventional types of carburetion, ease of maintenance, and simplicity of adjustment.

While I have shown and described the preferred form of my invention, I do not wish to be understood as limiting myself to the specific showing herein made, but do claim as a part of this invention all such modifications as defined in the following appended claim.

I claim:

In an injection type of carburetor, means to control the admission of fuel therein, said means including an elongated tubular housing, a cylindrical rack movable within said housing, a flanged tube in end alignment with said rack, said rack having a threaded end portion, means to join said rack and tube, said means comprising a bushing in threaded union with said rack and in flush contact with the flange on said tube, the body of said carburetor being formed with a bore 25 to receive said tube, an adjustable jet in said tube, and other jets in said tube, said last mentioned jets extending transversely thereof and being normally covered by said bore, said tube at its place of juncture with said rack having a passageway whereby fuel may flow therethrough to an area in direct communication with the first of said jets and in direct communication with others of said jets upon withdrawal from said bore, means to conduct fuel to said tubular housing, means to conduct fuel from said jets to the 30 throat of a Venturi tube in said carburetor for admixture with air, and means to actuate said cylindrical rack.

EARL G. ECKENBERG.
